UNITED STATES PATENT OFFICE.

JOHN C. WILSON, OF BOSTON, MASSACHUSETTS, ASSIGNOR TO THE AUTOMATIC TIME STAMP COMPANY, OF PORTLAND, MAINE, A CORPORATION OF MAINE.

TIME-STAMP.

SPECIFICATION forming part of Letters Patent No. 743,408, dated November 3, 1903.

Application filed August 15, 1899. Serial No. 727,340. (No model.)

To all whom it may concern:

Be it known that I, JOHN C. WILSON, of Boston, in the county of Suffolk and State of Massachusetts, have invented certain new and useful Improvements in Time-Stamp, of which the following is a specification.

This invention relates to the production of a simple machine for printing the actual time and determining or indicating the lapse of time or measuring or calculating and recording the time elapsing or intervening between one act or operation and another or automatically indicating or calculating the time which has been consumed or has lapsed between one time and another.

In carrying out the invention I utilize the devices for printing or recording time shown and described in United States Patent No. 576,644, granted to John C. Wilson February 9, 1897, to which reference may be had.

My invention consists of certain novel features hereinafter described, and particularly pointed out in the claims.

In the accompanying drawings, which illustrate a construction embodying my invention, Figure 1 is a side elevation of the time-stamp, a part of the casing or shell inclosing the clock-train being broken away to show the connection of the time-printing dies with the usual clock-train. Fig. 2 is a plan view of the same. Fig. 3 is a plan view of the time-printing dies and the bed-plate which directly supports them with the ribbon-holding device removed. Fig. 4 is a plan view of a card, ticket, or slip bearing upon its surface a printed representation of a time-dial divided in this instance into half-minute intervals or having one hundred and twenty equidistant divisional lines arranged circumferentially. Fig. 5 is an enlarged plan view of two successive imprints made by the time-stamp upon a card in connection with the printed time-dial shown in Fig. 4 to indicate the actual and lapsed time. Fig. 6 is a sectional detail view of the printing-dies, showing their connection with each other. Fig. 7 is a perspective view of the device for positioning the card or slip to be imprinted.

Like letters of reference refer to like parts throughout the several views.

As shown in Fig. 1, the machine consists of a hollow bell-shaped shell or casing A, containing a clock time-train of the usual construction (such as is shown in the patent above referred to) in its lower portion and adapted to allow a bed-plate B to be attached to a hollow upward extension B'. A curved arm C extends outwardly and upwardly from one side of the shell or casing A, and at its upper end it is provided with a tubular socket or sleeve D, through which is extended a plunger or rod E, provided at its lower extremity with a platen F and at its upper end with an operating knob or handle G, these parts being connected together and operating in the usual well-known manner, as shown in the above-mentioned patent. The bed-plate B is fastened to the upper surface of the shell or casing A by screws, (not shown,) and the clock-train is attached to the under inner surface of the shell or casing A in the same manner as shown in the above-mentioned patent. The outer printing-die H is supported by and revolves upon the surface of the bed-plate B, as shown in Fig. 3, and it is connected with the hour-sleeve I of the clock-train by means of a hollow stem J, extending to the center of the said die H through the hollow extension B' of the shell or casing A. Inside of an annular recess K in the outer printing-die H another printing-die L is placed, and it is connected with the minute-arbor M of the clock-train by a stem N, extending through the hollow stem J of the outer printing-die H. As shown in this instance, the outer printing-die H carries a small triangle or arrow-head O upon its upper and outer edge in printing form, and it is revolved by the clock-train once every twelve hours, while the inner printing-die L makes a revolution once in an hour. The inner or minute-printing die L has engraved upon its surface in printing form a series of graduated lines or marks L², preferably distributed over one-half of its circumference and which may be of any suitable degree of fineness or length of any desired number and which may have, as shown, significant figures or characters associated with them progressively arranged to facilitate the reading of the imprint made by the stamp, and the initial

or first line of the series of graduated lines or marks L^2 may be a long pointed marker or index to indicate the minute-hand in the imprint and to point out or indicate the actual time and also the elapsed or intervening time between successive imprints, as shown in Fig. 5.

As is common in the operation of time-stamps the imprinting is made through an inking-ribbon P , carried in a ribbon frame or holder P' of usual construction, the sides of the frame being slotted at P^2 in order that it may be held firmly in place upon the bed-plate by engagement with the pins P^3 , extending from the sides of the bed-plate B . The inking-ribbon may be shifted in the usual way by turning the shafts upon which it is rolled by means of the thumb-screws P^4 .

A positioning device Q for the card or slip to be imprinted is attached to the frame of the ribbon-holder P' by suitable screws Q' , and it consists of two pieces of thin metal attached to the frame of the ribbon-holder at right angles to each other, as shown in Fig. 7, and extending upwardly above the surface of the inking-ribbon P . One piece is attached to one of the sides of the ribbon-holder P' and is parallel thereto, while the other piece is parallel to the back end of the ribbon-holder P' , to which it is fastened, as above described.

One of the cards or slips R to be imprinted is shown in Fig. 4 with a graduated time-dial R' printed upon it at a certain fixed distance from its upper edge R^2 and its left-hand edge R^3 , and the positioning device Q must always be fixed in such a position relatively to the printing-surfaces of the printing-dies H and L and to the printed time-dial R' upon the card or slip R that when the latter is turned over and is placed with its upper and right-hand edges bearing against the corresponding end and side of the positioning device Q the imprints made by the outer and inner printing-dies H and L will always be in a proper and unvarying concentric relation to the printed time-dial R' , as shown in Fig. 5. It is plain from this description that if two successive imprints should immediately follow one another when the card or slip is in the above position then they would be exactly superimposed and that the concentric variation from this exact superimposition of any two successive imprints would measure, indicate, or record the time elapsing or intervening between them.

The bed-plate B is provided with a slot T , into which, if desired, printing-types may be inserted to print the day, month, and year. To illustrate the operation of the machine, referring to Figs. 3, 4, and 5: Suppose that a card or slip R with a time-dial R' printed upon it in the proper place be inserted under the platen F and properly positioned, as above described, and that by depressing the platen twice in succession the card or slip R is imprinted, as shown in Fig. 5. In such a case

the first imprint would exhibit a long initial line S upon the card or slip R , extending from the center to the inner extremity of the line or pointer-mark on the time-dial R' , (marked "2,") and also thirty shorter lines extending from near the inner ends of the time-dial lines or marks toward the center of the imprint. As shown in Fig. 5, these shorter lines or marks are graduated into and represent minutes, and for convenience of reading every fifth minute is represented by a dotted line with the figures "5," "10," "15," "20," "25," and "30" attached to each in a progressive manner. This first imprint would therefore consist of the long line or pointer-mark S , before mentioned, pointing to the line or mark on the time-dial marked "2" and the dotted lines marked "30," "25," "20," "15," "10," and "5" extending inwardly from the time-dial figures "8," "7," "6," "5," "4," and "3," respectively, and the intermediate minute lines or marks extending inwardly from the eleventh, twelfth, thirteenth, fourteenth, fifteenth, sixteenth, seventeenth, eighteenth, nineteenth, twenty-first, twenty-second, twenty-third, twenty-fourth, twenty-sixth, twenty-seventh, twenty-eighth, and twenty-ninth of the time-dial. From this it will be seen that the inner or minute-printing die L imprints a measured or graduated series of marks or lines progressively arranged from left to right and which may or may not coincide with the corresponding graduated or divisional marks of the time-dial R' , according to the position of the minute-printing die L at the moment the imprint is made. The first imprint under consideration would also show, as in Fig. 5, the triangular mark or arrow-head O' , indicating the hour and pointing inwardly near the outer end of the forty-sixth minute-mark on the time-dial R' , the hour and minute being shown as ten minutes past nine. If the card or slip R bearing the first imprint, as just described, is again imprinted in the same manner, the long line pointer-mark S' and the arrow-head O^2 of the second imprint would indicate twenty-seven minutes and a quarter past nine, as shown in Fig. 5. By subtracting the time of the first imprint (9.10) from that of the second imprint (9.27 $\frac{1}{4}$) the interval of time between the imprints is found to be seventeen and one-quarter minutes.

Although the described arrangement of successive imprints in conjunction with a single time-dial, as shown, enables the interval of time between them to be determined more readily than would be possible with two separate and independent time-imprints, yet it is desirable in many cases to be able to ascertain the interval or lapsed time automatically without calculation of any kind, and this invention accomplishes this result in the most simple manner.

Referring again to Fig. 5, it will be noticed that the inner printing-die H in making the second imprint in part superimposes it upon

or over the first imprint, or, as shown in Fig. 5, it is superimposed between the long line S', which marks the beginning of the second imprint, and the dotted line "30," denoting the 5 ending of the first imprint, and of course this superimposition varies in extent and in position in correspondence with the interval of time elapsing between the two imprints. No confusion, however, in reading the lapsed 10 time results from this superimposition, as it is always absent from that part of the imprint which indicates the elapsed or intervening time, and the line S', marking the initial or starting point of the second imprint, in all 15 cases points to the exact interval of time existing between the two imprints—as, for instance, as shown in Fig. 5 it points to two minutes and one-quarter beyond the fifteen-minute dotted line and indicates a total interval 20 of seventeen and one-quarter minutes, as before determined by subtraction.

Although I have spoken of the figures or characters progressively arranged in connection with the graduated or divisional time- 25 marks upon the inner printing-die L as signifying minutes, yet it is clear that a different significance—such, for instance, as progressive values or charges—may be attached to them, if desired, and the graduated lines 30 may be greater or less distances apart, or that the calculating printing-die, where it is required to calculate longer intervals of time, might easily be run at a less rate of speed, or where it is desired to compute shorter intervals 35 at a higher rate of speed than that shown and described.

While I have shown and described a card or slip with the representation of a clock-dial previously printed on the same and claimed 40 the same in combination with a rotatable time-printing die of special construction to indicate lapses of time by the differences in the superimposition of imprints by the same and recording the actual time of the imprint 45 in connection with the previously printed clock-dial, yet I have in another application, Serial No. 172,646, filed September 10, 1903, shown, described, and claimed a card or slip having the representation of a clock-dial previously 50 printed on the same for use in conjunction with a rotating time-printing die of usual construction, the imprint from which when read in conjunction with a previously imprinted clock-dial indicates and records 55 the actual time only.

I do not limit myself to the arrangement and construction shown, as the same may be varied without departing from the spirit of my invention.

Having thus ascertained the nature of my invention and set forth a construction embodying the same, what I claim as new, and desire to secure by Letters Patent of the United States, is—

1. In an apparatus of the character described, a movable printing-die having a graduated segmental printing-surface, an imprint-

ing-platen coöperating with the said graduated printing-surface, and a positioning device to enable the card or slip to be printed 70 to be placed in an unvarying printing relation to the printing-surface of the said movable printing-die to cause successive imprints of said die to be superimposed, the extent of the superimposition of the successive imprints 75 indicating, measuring and recording the extent of the movements of the said movable printing-die between the successive imprints.

2. In an apparatus of the character described, a rotatable printing-die having a graduated segmental printing-surface, an imprinting-platen coöperating with the said graduated printing-surface, and a positioning device to enable the card or slip to be printed 80 to be placed in an unvarying concentric printing relation with the said rotatable printing-die to cause successive imprints of said die to be superimposed, the extent of the superimposition of the successive imprints indicating, measuring and recording the distance 85 the said rotatable printing-die has been rotated between the successive imprints.

3. In an apparatus of the character described, a movable printing-die having a graduated segmental printing-surface including an initial pointer-mark or index, an imprinting-platen coöperating with the said movable printing-die, and a positioning device to enable the card or slip to be printed to be placed 90 in an unvarying position relatively to the said movable printing-die to cause successive imprints of said die to be superimposed, the extent of the superimposition of the successive imprints being indicated in the resultant im- 95 print by the positions of the said initial pointer-mark or index relatively to the imprints of the said graduated printing-surface.

4. In an apparatus of the character described, a rotatable time-printing die having 100 a graduated segmental surface indicating divisions of time, mechanism for actuating said time-printing die to a predetermined rate of rotation, an imprinting-platen coöperating with the said time-printing die, and a positioning device to enable the card or slip to be printed to be placed in an unvarying printing relation with the said rotatable time-printing die to cause successive imprints of said die to be superimposed, the extent of the superimposition of the successive imprints indicating, measuring and recording the time 110 elapsing or intervening between successive imprints of the said rotatable time-printing die. 115

5. In an apparatus of the character described, a rotatable time-printing die having a graduated segmental printing-surface indicating divisions of time including an initial pointer-mark or index, mechanism for actuating said time-printing die to a predetermined rate of rotation, an imprinting-platen coöperating with the said rotatable time-printing die, and a positioning device to enable 120 125 130

the card or slip to be printed to be placed in an unvarying printing position relatively to the said rotatable time-printing die to cause successive imprints of said die to be superimposed, the time elapsing or intervening between the successive imprints being automatically indicated in the resultant imprint by the positions of the said initial pointer-mark or index relatively to the imprints of the said graduated printing-surface.

6. In an apparatus of the character described, a rotatable time-printing die having a graduated segmental printing-surface including an initial pointer-mark or index and figures or characters at different points indicating divisions of time, mechanism for actuating the said rotatable time-printing die to continuous rotation, an imprinting-platen coöperating with the said rotatable time-printing die, and a positioning device to enable the card or slip to be printed to be placed in an unvarying position with relation to the said rotatable time-printing die to cause successive imprints of the said die to be superimposed, the time elapsing or intervening between the successive imprints being indicated in the resultant imprint by the positions of the said initial pointer-mark or index relatively to the imprints of the said graduated printing-surface and the said characters or figures.

7. In an apparatus of the character described, a rotatable printing-die having a graduated printing-surface extending over a segment of a circle, an imprinting-platen coöperating with the said printing-surface, and a positioning device with which one end and one side of the card engages to enable the card or slip to be printed to be placed in an unvarying position with relation to the said graduated printing-surface to cause successive imprints of said die to be superimposed, the extent of the superimposition of the successive imprints indicating, measuring and recording the distance the said rotatable printing-die has been rotated between the successive imprints.

8. In an apparatus of the character described, a rotatable time-printing die having a graduated printing-surface indicating divisions of time extending over a segment of a circle and including an initial pointer-mark or index, mechanism for rotating said time-printing die at a predetermined speed, an imprinting-platen coöperating with the said time-printing die, and a positioning device with which one end and one side of the card engages to enable the card or slip to be printed to be placed in an unvarying position with

relation to the said time-printing die to cause successive imprints of said die to be superimposed, the time elapsing or intervening between the successive imprints being automatically indicated in the resultant imprint by the positions of the said pointer-mark or index relatively to the imprints of the said graduated printing-surface.

9. In an apparatus of the character described, a rotating time-printing die having a graduated segmental printing-surface and provided with an initial pointer-mark or index, a clock-train connected with the said time-printing die to rotate the same at a predetermined speed, an imprinting-platen coöperating with the said rotating time-printing die, and a positioning device to enable the said rotating time-printing die to be printed upon a card or slip in an unvarying position concentric with a representation of a clock-dial previously printed upon the same card or slip.

10. In an apparatus of the character described, a rotating time-printing die having a graduated segmental printing-surface and provided with a pointer-mark or index, a clock-train connected with the said time-printing die to rotate the same at a predetermined speed, an imprinting-platen coöperating with the said rotating time-printing die, and a positioning device to enable the said rotatable time-printing die to be printed upon a card or slip concentric with and inside of a representation of a clock-dial previously printed upon the same card or slip.

11. In an apparatus of the character described, a rotating time-printing die having a graduated segmental printing-surface and provided with a pointer-mark or index representing a minute-hand, and another rotating time-printing die provided with a pointer-mark or index representing an hour-hand, a clock-train connected with and actuating both of the said rotating time-printing dies at predetermined speeds, and a positioning device to enable the said rotating time-printing dies to be printed upon a card or slip in an unvarying concentric relation with a representation of a clock-dial previously printed upon the same card or slip.

In testimony whereof I have signed my name to this specification, in the presence of two subscribing witnesses, this 1st day of August, A. D. 1899.

JOHN C. WILSON.
